UNITED STATES PATENT OFFICE.

FREDRICK C. MATHEWS, OF DETROIT, MICHIGAN, ASSIGNOR TO MATHEWS, KAYE, MANN & CO., OF DETROIT, MICHIGAN, A CORPORATION OF MICHIGAN.

FOLDER.

977,814.

Specification of Letters Patent.

Patented Dec. 6, 1910.

Application filed March 28, 1910. Serial No. 551,843.

To all whom it may concern:

Be it known that I, FREDRICK C. MATHEWS, a citizen of the United States of America, residing at Detroit, in the county of Wayne and State of Michigan, have invented certain new and useful Improvements in Folders, of which the following is a specification, reference being had therein to the accompanying drawings.

10 This invention relates to such advertising folders which are marketable as postcards and to which a return postcard blank is attached and the invention consists in the novel construction, arrangement and combination of a folder and a return postal card all as more fully hereinafter described and shown in the accompanying drawings, in which—

Figure 1 is an elevation of my return post 20 card folder ready for mailing; Fig. 2 shows the folder with the attached return post card opened; Fig. 3 is a perspective view showing the folder partly closed; and Fig. 4 is a cross section of Fig. 1.

25 A represents the folder proper and B the return postal card both made of a single sheet of suitable cardboard with the latter partially separated by a line of perforations α .

30 The return postal card B is preferably of a regulation size while the folder proper is of greater dimensions and more than twice as large, so that when folded in the middle as shown it is of greater length and width than the postal card.

The part A is provided with a slit C some distance below the top of it and of a length to correspond to the lateral dimension of the part B as will appear more fully herein- 40 after. The part A has the printed advertising matter on the side corresponding to that on which the return address is printed on the postal card, and in mailing the folder the part A is first folded upon itself and 45 then the part B is folded upon the part thereof which bears the slit C and thence inserted with its free edge into the slit as shown in Fig. 3, and pressed together so that the lower part of the reverse side of the 50 postal card remains exposed as shown in

Fig. 1. The slit C it will be seen leaves enough of the postal card exposed to write thereon the address of the party to whom the folder is to be mailed and in connection with suitable indication printed upon the adjacent uncovered part of the folder, the same is fully identified to be mailable as a postal card.

The advantage of my folder aside from its simplicity is that the address of the party to whom the folder is mailed is not placed on the folder proper but on the return post card upon the reverse side thereof in the place where the user would sign his name after filling out the order blank printed thereon above his name. The addressee to whom the folder is directed is thus relieved of signing his name and address in returning the postal card and mail order houses and other concerns using folders of this character in carrying on their business are relieved of the constant trouble of receiving orders from persons who either entirely forget to sign their names or addresses, or whose name and address is undecipherable on account of poor writing or having been obliterated by signing with a lead pencil.

What I claim as my invention is:—

1. A return postal card folder comprising a body portion [bearing a printed communication upon one side] and a postal card attached to one edge thereof and [bearing the address of the sender upon the same side,] the body portion being wider than the postal card and provided near its opposite edge with a slit corresponding to the width of the postal card and adapted to coöperate therewith to form a tongue and slit closure by inserting the postal card into the slit when the body portion is folded.

2. A return postal card folder made of one piece of card board with a body portion having the advertising matter printed upon one side and a postal card portion attached to one edge thereof and bearing the address of the sender upon the same side with the advertising matter, the body portion being wider than the postal card portion and provided with a slit adjacent to the edge opposite to that to which the post card portion is

attached and adapted to coöperate with the postal card portion to form a tongue and slit closure for the body portion when the same is folded upon itself and to leave a 5 suitable portion of the postal card portion exposed to serve as a place for the address in mailing.

In testimony whereof I affix my signature in presence of two witnesses.

FREDRICK C. MATHEWS.
